UNITED STATES PATENT OFFICE.

ALFRED E. SELIGER, OF ST. PAUL, MINNESOTA.

DESIGN FOR A FRAME FOR CLOCKS, PICTURES, OR SIMILAR ARTICLES.

SPECIFICATION forming part of Design No. 37,104, dated August 23, 1904.

Application filed July 2, 1904. Serial No. 215,184. Term of patent 3½ years.

To all whom it may concern:

Be it known that I, ALFRED E. SELIGER, a citizen of the United States, residing at St. Paul, in the county of Ramsey and State of Minnesota, have invented a new, original, and ornamental Design for a Frame for Clocks, Pictures, or Similar Articles, of which the following is a specification, reference being had to the accompanying drawing, forming part thereof.

The figure is a view of the front of a frame

for clocks, pictures, or similar articles, showing my new design.

What I claim as new, and desire to protect by Letters Patent, is—

The ornamental design for a frame for clocks, pictures, or similar articles, as shown.

ALFRED E. SELIGER.
